UNITED STATES PATENT OFFICE

SAMUEL A. SCHWARTZ, OF ST. PAUL, MINNESOTA

TOWEL CABINET

Application filed November 12, 1931. Serial No. 574,493.

This invention relates to towel cabinets.

It is the general object of this invention to provide a novel and improved towel cabinet adapted for efficient use in lavatories and the like.

To this end, generally stated, the invention consists in the novel parts and novel combinations of parts hereinafter defined in the claims and described in the following specification, made in connection with the accompanying drawings, wherein like reference characters refer to the same or similar parts throughout the various views and in which,

Fig. 1 is a vertical section taken from front to rear through a towel cabinet embodying the invention with toweling in place therein;

Fig. 2 is a view in front elevation of the cabinet with the door opened, only a portion of the door being shown and the toweling being removed from the cabinet;

Fig. 3 is a view in outer side elevation of one of the side frames of the cabinet;

Fig. 4 is a view in outer side elevation of a portion of the other of the side frames;

Fig. 5 is a detailed view in outer side elevation of the mechanism for controlling the delivery of toweling from the cabinet, a portion of the door of the cabinet being shown in vertical section;

Fig. 6 is a similar view showing this same mechanism in a different position;

Fig. 7 is a view in inner side elevation of the bolt forming a part of the said mechanism; and

Fig. 8 is a view in inner end elevation of this same bolt.

In accordance with the invention, there is provided a casing 9 of rectangular shape and having an open front normally closed by a door 10 mounted on hinges 10a secured to the forward edge of one side of the casing. The casing 9 has solid sides, top and back and it is partly closed at its bottom by means of a slat 11, the forward edge of which is spaced rearwardly slightly from the front of the casing to provide a slot 12 between the forward edge of the slat and the door 10 when the door is closed. The rear edge of the slat 11 is spaced forwardly some distance from the back of the casing to form quite

a large opening 13 in the bottom of the casing. The door 10 may be equipped with a mirror 14, as is usual in towel cabinets, and eyes 15 may be secured to the upper portion of the back of the casing to permit the cabinet to be hung on a wall or the like. A pair of side frames 16 and 17 respectively, are provided and these side frames are similarly formed with the exception that one of the side frames, as the side frame 16, is adapted for use at the right side of the casing and the other of the side frames 17 is adapted for use at the left side of the casing. Each side frame extends from the bottom of the casing to adjacent the top thereof and the side frame 16 fits against and is secured to the right side of the casing, while the other side frame 17 fits against and is secured to the left side of the casing. Both side frames have outturned flanges at the four edges thereof and their body portions are therefore spaced inwardly somewhat from the sides of the casing. Adjacent their lower edges, the two side frames have horizontal guide slots 18 formed therein, which extend from front to rear of the casing. A sliding trough 19 has side flanges 20 which fit within the guide slots 18 to permit the trough to be slid forwardly through the front opening of the casing 9 when the door 10 is opened, while also permitting the trough 19 to be slid rearwardly to such a point that the front of the trough will not project beyond the forward edge of the slat 11. The trough 19 as best shown in Fig. 1, has a concave upper portion within which a roll 21 of clean toweling A may be supported. The back part of the concave portion of the trough 19 projects considerably above the front part of the concave portion. The lower rear edge of the trough 19 is rounded as shown at 22 and when the door 10 is closed, this rounded rear edge 22 will be forced rearwardly so that it is spaced closely from the back of the casing. A pair of rubber pins 23 secured to the rear side of the door 10 adjacent the two edges thereof engage the front of the trough 19 when the door is closed to hold the trough in extreme rearwardly slid position under slight resilient tension. Spaced above the

95

100

bottom of the trough 19 and secured to or formed integral with the trough, is a horizontal, rearwardly projecting interlocking member 24, preferably having a rounded rear edge. In the embodiment of the invention shown, the trough 19 is shown as being formed from sheet metal and the sheet metal is reversely bent on itself to form the interlocking member 24. For cooperation with the interlocking member 24, there is secured to the back of the casing a channeled, horizontal interlocking member 25, which may be also formed of sheet metal. When the trough 19 is rearwardly slid in the casing, it will be seen that the interlocking member 24 will fit within the channel of the interlocking member 25, so as to substantially fill the channel therein. It is, of course, obvious that if desired, the male interlocking member 24 may be applied to the back of the casing, while the female interlocking member 25 may be applied to the trough 19.

The trunnions of a sandpaper covered, clean towel feed roller 26 are journaled in the two side frames 16 and 17 adjacent the forward edges thereof and above the position of the clean towel roll 21. This roller 26 is also located above the upper edge of the trough 19, so that the trough may be removed from the casing 9, while the roller 26 remains in place. For cooperation with the roller 26, there is provided a pinch roll 27 having trunnions journaled in the side frames 16 and 17 above and slightly forward of the feed roller 26. The two rollers 26 and 27 are spaced only sufficiently far apart to receive therebetween the web of toweling A drawn from the clean towel roll 21. The trunnion of a sandpaper covered, soiled towel feed roller 28 are journaled in side frames 16 and 17 centrally between the front and rear edges thereof considerably above the rotating axis of the clean towel feed roller 26. Angular slots 29 are cut in the side frames 16 and 17 above the soiled towel feed roller 28 and these slots project vertically for some distance and then project horizontally to the forward edges of the side frames. A soiled towel take-up roller 30 has trunnions which fit within the angular slots 29 and this roller together with whatever toweling A that is wound thereon, rests by gravity against the feed roller 28. Sprockets 31 and 32 respectively are secured to the left trunnions of the respective feed rollers 26 and 28, between the side frame 17 and the left side of the casing 9, and an endless sprocket chain 33 is trained over the two sprockets 31 and 32.

Mounted on the right hand trunnion of the soiled towel feed roller 28, between the side frame 16 and the right side of casing 9, is a disk 34, best illustrated in Figs. 5 and 6. A pair of outwardly projecting pins 35 and 36 respectively are secured to this disk 34 and in the particular arrangement shown, the pin

35 is readily spaced closer to the center of the disk than is the pin 36 and the pin 36 is located in circumferentially spaced relation from the pin 35 a number of degrees in advance of the pin 35 relative to the normal direction of rotation of the disk 34. Secured to the side frame 16 between the side frame and the right side of casing 9, is a channel shaped guide casing 37 horizontally disposed and having an inturned flange at its forward end. A sliding bolt 38 is mounted within the channel of the guide casing 37 for sliding movement forwardly and rearwardly therein, and this bolt has a forwardly projecting pin 39 which extends through a notch in the inturned forward flange of the guide casing 37 and also through an opening in the forward flange of the side frame 16. The door 10 has an opening 40 cut therein adapted to be alined with the pin 39 when the door is closed, and the door is recessed to enlarge opening 40 at the two sides of the door to accommodate a shouldered push button 41, the sliding movement of which is limited in one direction by the shoulder of the push button and is limited in the other direction by a screw 41a preventing the push button from being completely removed from the opening 40. A coiled pressure spring 42 bears at one end against the inturned forward flange of guide casing 37 and this spring surrounds the pin 39 and is anchored at its other end to the pin. This spring, accordingly, normally urges the bolt 38 forwardly or toward the front of the casing. When the door 10 is closed, the possible forward movement of the bolt 38 is limited by engagement between the forward end of the pin 39 and the screw 41a of the push button 41. When the door 10 is opened, further forward movement of the bolt is possible, this movement being limited only by engagement of the forward end of the bolt proper with the inturned forward flange of the guide casing 37. The bolt 38 and pin 39 are of such length and are so disposed relative to the disk 34 that when the door 10 is closed, the lower rear corner of the bolt will overlie the upper forward portion of the disk, the inner rear corner of the bolt being cut away at 38a to receive this portion of the disk. A deeper cut or channel 38b is also made in the lower rear corner of the bolt to form two shoulders 38c and 38d spaced from each other on the bolt. The channel 38b is of sufficient depth to permit the pins 35 and 36 to pass through this channel without striking the bolt 38, if the pins 35 and 36 happen to be alined with this channel as the disk 34 is rotated. The shoulders 38c and 38d are so positioned relative to the pins 35 and 36 that when the door 10 is closed and the push button 41 is forwardly extended to its extreme position, as shown in Fig. 5, the shoulder 38c will be in the path of movement of the pin 35, and the pin 36, when the pin 35 engages the shoulder 38d.

38c, will be in the path of movement of the shoulder 38d as the bolt 38 is slid rearwardly by pressing the push button 41. Assuming the parts are in position as shown in Fig. 5, 5 rotation of the disk 34 and of the feed rollers 26 and 28 in a clockwise direction, as viewed in Figs. 5 and 3, will be prevented by the engagement of pin 35 with shoulder 38c. As the push button 41 is pressed inwardly, the 10 shoulder 38d will strike the pin 36 and thereby rotate the disk 34 for a short distance. The channel 38b is so placed relative to the pin 35, that as this occurs the shoulder 38c will be carried rearwardly beyond the pin 15 35 and the pin 35 will be swung to the position shown in Fig. 6 within the channel 38b. Of course, shortly after the parts have taken the position shown in Fig. 6, the spring 42 upon release of the push button 41, will move 20 the bolt 38 back to its original position as shown in Fig. 5, but the pin 35 will no longer engage the shoulder 38c and as a result, it will be possible to rotate the disk 34 through nearly a complete revolution, or until the pin 25 35 again strikes the lower side of the shoulder 38c. During this latter movement, the pin 36 will freely pass through the channel 38b of the bolt, to again assume its original position as shown in Fig. 5. If the door 10 30 should be opened, the spring 42 will immediately move the bolt 35 forwardly to such a position that the lower rear corner of the bolt will not overlie the disk 34 and as a result, it will be perfectly possible to rotate the disk 35 without interference by the bolt 38 when the door 10 is open.

To fill the cabinet and set it up ready for use, the door 10 will be first opened whereupon the trough 19 will be grasped and slid forwardly. A roll 21 of clean toweling A may then be deposited within the trough, whereupon the free end of the toweling A will be grasped and carried up over the clean towel feed roll 26 to a point between the roll 45 26 and the pinch roll 27. As the bolt 38 with the door open is projected forwardly beyond the disk 34, it is possible to freely rotate both feed rolls 26 and 28 without interference by the bolt 38 and the web of toweling A may 50 be readily threaded between the clean towel feed roll 26 and the pinch roll 27 by turning the feed roll 28 by hand in the direction shown by the arrow adjacent thereto in Fig. 1. The web of toweling after being threaded 55 between the two rolls 26 and 27 will be carried over the pinch roll 27 and thence downwardly forward of the front of the trough 19 and the front edge of the slat 12. A considerable quantity of the toweling A will now be drawn 60 from the clean towel roll 21 to form a loop of toweling of the desired length below the cabinet. As the trough 19 is slid forwardly at this time, from the back of the casing, it will now be easy for the person filling the 65 cabinet to carry the free end of the toweling

A through the opening 13 and upwardly between the back of the casing and the rear part of the trough 19. After this has been done, the free end of the toweling A will be carried above the soiled towel feed roll 28, whereupon 70 if desired, the soiled towel take-up roll 30 may be removed from the slots 29 and the free end of the toweling can be wound upon this roll 30. The roll 30 can then be reinserted in place within the slots 29 so that this roll, 75 together with whatever toweling is wound thereon, rests directly upon the soiled towel feed roll 28. The trough 19 may now be slid rearwardly to cause the interlocking member 24 to be received within the channel of the 80 interlocking member 25 and thereby frictionally clamp the toweling at this point between these members. The door 10 may now be closed, whereupon the rubber pins 33 bearing upon the front of the trough 19 will maintain 85 the trough in its rearwardly slid position.

The cabinet is now ready for use. A loop of toweling A will extend from the slot 12 at the forward portion of the bottom of the cabinet downwardly and thence upwardly 90 through the opening 13 between the back of the cabinet and the rounded rear edge 22 of the trough 19. A person wishing to wipe his hands on a fresh piece of toweling may press the push button 41, release the same and then draw downwardly on the front run of the depending loop of toweling. As the push button 41 is pressed, assuming that rotation of the feed rollers 26 and 28 has hitherto been impossible by engagement of the pin 35 with the shoulder 38c of the bolt 38, the disk 34 will be given a short initial rotation by engagement of the shoulder 38d with the pin 36 as has been above explained, whereupon the disk 34 will be unlocked or released to permit the free rotation of the disk 34 and the two rollers 26 and 28 through the balance of a complete revolution as the front run of the loop of toweling A is drawn downwardly. 100 As the movement of the toweling A occurs, the same quantity of toweling that is drawn from the clean towel roll 21 will be wound upon the soiled towel take-up roller 30. The two interlocking members 24 and 25 place sufficient friction on the towel web, prior to 105 its passage to the soiled towel take-up roller 30, that the toweling will not overrun on the take-up roller as the operator ceases to pull the toweling. As a result, the soiled toweling will be evenly wound onto the roller 30 110 115 and it will be tightly wound thereon. After the operator has pulled downwardly on the front run of the depending loop of toweling A for a short time, the pin 35 will be rotated to such a position that it again engages the shoulder 38c whereupon further movement of the feed rollers 26 and 28 and further dispensation of clean portions of the toweling will be prevented until the push button 41 is again pressed inwardly. 120 125 130

My mechanism for controlling the delivery of toweling from the cabinet is an improvement on the towel delivering mechanism disclosed in United States Patent No. 1,256,821, issued to R. E. Hudson and W. P. Bickley on February 12, 1918, entitled "Towel holder". It is very important, in order that my cabinet may be loaded, that the two feed rollers 26 and 28 be capable of free rotation, while the towel web is being threaded in its proper position. In my cabinet whenever the door 10 is open, free rotation of both feed rollers 26 and 28 can take place, and yet when the door is closed, it is only possible to pull out a small section of toweling after the push button 41 has been once pressed. Attention should be called to the fact that when the door 10 is closed, if the rear run of the loop of toweling A is pulled downwardly, only a small quantity of soiled toweling can be withdrawn from the soiled towel take-up roll 30. Assuming that the delivery mechanism is in the position shown in Fig. 5, as the rear run of the loop of toweling is pulled downwardly, the two rollers 26 and 28 can only be turned in a counterclockwise direction as viewed in Fig. 3, and in a clockwise direction as viewed in Fig. 1 until the disk 34 has been turned in a counterclockwise direction, as viewed in Fig. 5 to nearly a complete revolution or until the pin 35 strikes the upper portion of the shoulder 38c. It will thus be impossible for an unauthorized person to pay out a large quantity of soiled toweling from the cabinet.

It will be seen that a cabinet has been provided which can be very easily loaded and efficiently operated. The soiled toweling is kept from contact with the clean toweling at all times and the cabinet is thus sanitary.

It will, of course, be understood that various changes may be made in the form, details, arrangement and proportions of the various parts without departing from the scope of the present invention. Although the cabinet illustrated is a wall cabinet, it will, of course, be understood that the invention may be embodied in floor cabinets and cabinets of other types.

What is claimed is:—

1. In a towel cabinet, soiled towel take-up means located forward of the back of the cabinet and a member slidably mounted below said take-up means for forward movement and rearward movement against the back portion of the cabinet, said member and cabinet having cooperating guide flanges and grooves whereby when said member is forwardly slid, toweling may be threaded from below said member upwardly to said take-up means between said member and the back portion of the cabinet and after the toweling is threaded said member may be slid rearwardly to cause frictional engagement of the

toweling between said member and the back of the cabinet.

2. A towel cabinet having a front opening, a door normally closing said opening, soiled towel take-up means located forward of the back of the cabinet and a member slidably mounted below said take-up means for movement forwardly through said opening when said door is open and for movement rearwardly against the back portion of the cabinet whereby, when said door is open and said member is forwardly slid, toweling may be threaded from below said member upwardly to said take-up means between the back of the cabinet and said member and after the toweling is threaded, said member may be slid rearwardly to cause frictional engagement of the toweling between said member and the back portion of the cabinet, said door when closed engaging the forward portion of said member to prevent forward movement thereof.

3. A towel cabinet having a front opening and a hand receiving opening at its bottom adjacent its back, towel holding means in the cabinet, feeding means permitting toweling to be fed downwardly below the cabinet from adjacent the front portion thereof, soiled towel take-up means in the cabinet to which the toweling may run after depending in a loop below the cabinet and after passing upwardly through said hand receiving opening, a sliding member having a horizontal lower portion of approximately the same width as the depth of the cabinet, said sliding member being movable forwardly through said front opening and movable rearwardly within the cabinet to cause the horizontal portion thereof to close off the major portion of said hand receiving opening, said sliding member and the back of the cabinet having cooperating friction portions adapted to engage the toweling therebetween when said sliding member is rearwardly slid.

4. A towel cabinet comprising a casing having a front opening, a door normally closing said opening, said cabinet having a bottom with a hand receiving opening adjacent the back thereof, clean towel holding means within the cabinet, feeding means permitting toweling to be fed from said holding means downwardly below the bottom of the cabinet adjacent the front thereof, soiled towel take-up means in said cabinet to which the toweling may run after passing upwardly from the bottom of the cabinet through said hand receiving opening, a sliding member mounted below the soiled towel take-up means for forward extension therefrom when the said door is open, and for rearward movement toward the rear of the cabinet, said sliding member closing the major portion of said hand receiving opening when slid rearwardly in the cabinet and interlocking members carried by said sliding member and the back

of the cabinet between which the toweling extends, said interlocking means being adapted to clamp the toweling therebetween when said sliding member is in rearwardly slid position, said door when closed preventing forward sliding movement of said sliding member.

5. A towel cabinet comprising a casing having a front opening, a door normally closing said opening, said casing having a hand receiving opening at its bottom near its back, a trough within which a roll of clean toweling may be held and slidably mounted below the soiled towel take-up means for forward extension through said front opening when the door is open, said trough having a horizontal lower portion of approximately the same width as the depth of the cabinet, which lower portion when the trough is rearwardly slid closes off the major portion of said hand receiving opening, said trough having a portion at its lower rear edge normally disposed adjacent the back of the casing, means for delivering clean toweling downwardly from said casing adjacent the front thereof, means above said trough for taking up the soiled toweling, whereby the toweling may depend below the bottom of the cabinet in a loop and extend upwardly to said take-up means between the back of the casing and said trough and a pair of cooperating interlocking members mounted respectively on said trough and the back of the casing and between which the toweling extends, said interlocking members acting to frictionally grip the toweling prior to its passage to said take-up means.

6. A towel cabinet comprising a casing having a loading opening, a door normally closing said opening, means for holding a supply of clean toweling within said casing, a clean towel feed roller over which the toweling may be drawn for dispensation, a soiled towel take-up roller within said casing and to which the soiled toweling may be carried, a soiled towel feed roller for operating said take-up roller, means connecting said feed rollers together for simultaneous rotation, mechanism including an actuating member for locking said feed rollers against movement when said door is closed and permitting a limited movement of said feed rollers as said actuating member is operated, said mechanism being automatically disengaged from said feed rollers when said door is opened.

7. In a towel cabinet, a casing having a loading opening, a door normally closing said opening, a feed roller over which toweling may be drawn as toweling is dispensed from the cabinet, mechanism, including an actuating member, held in position by said door when closed to normally prevent rotation of said roller but permitting rotation of said roller as said actuating member is oper-

ated, said mechanism when the door is opened being moved to a position to permit said roller to be freely rotated without operating said actuating member.

8. In a towel cabinet, a casing having a clean towel loading opening therein, a door normally closing said opening, means for supporting a quantity of clean toweling within the casing, a feed roller over which the toweling must travel during the dispensing movement thereof, a member moving with said roller, a bolt slidably mounted in the cabinet and having an outer, a medial and an inner position, an actuating member for said bolt, resilient means urging said bolt to outer position, said door when closed engaging said actuating member to hold said bolt normally in its medial position, said bolt having a portion which when said bolt is in its medial position lies in the path of movement of said first mentioned member, said portion when said bolt is in its inner and outer positions being out of the path of movement of said first mentioned member, whereby as said door is opened, said bolt will be moved to its outer position to permit free rotation of said roller as the cabinet is loaded.

9. A towel cabinet comprising a casing having a front opening, a door normally closing said opening, means for holding a quantity of toweling within said casing, a feed roller over which the toweling must run as it is dispensed, detent means slidably mounted in said casing, a member located near said detent means and mounted for rotation with said roller, said door when closed holding said detent means normally in the path of movement of said member, resilient means urging said detent means outwardly beyond the path of movement of said member said detent means including an actuating member for moving said detent means inwardly out of the path of movement of said member when said door is closed, said resilient means moving said detent means outwardly beyond the path of movement of said member when said door is opened to permit free rotation of said roller as the cabinet is loaded.

10. A towel cabinet comprising a casing, means for holding a quantity of toweling within said casing, a feed roller over which the toweling must run as it is dispensed, a member mounted for rotation with said feed roller, a pair of projections carried by said member and spaced from each other, a bolt slidably mounted in said casing for extension to and from said member, resilient means urging said bolt away from said member, said bolt having a pair of spaced shoulders so disposed relative to said projections that when one of said projections engages one shoulder of said bolt, the other projection will lie in the path of inward movement of the remaining shoulder and as said bolt is slid inwardly, the first projection will be carried

beyond a point where it will engage the first mentioned shoulder, means normally holding said bolt in a position where said first mentioned projection will strike said first mentioned shoulder as said member is rotated, said last mentioned means being capable of disengagement from said bolt to permit the said resilient means to move said bolt to such a position that neither shoulder will engage either of said projections during rotation of said roller.

11. The structure defined in claim 10, said last mentioned means comprising a door normally closing a towel loading opening in said 15 casing.

In testimony whereof I affix my signature.
SAMUEL A. SCHWARTZ.
